UNITED STATES PATENT OFFICE.

JAMES H. RAND, JR., OF TONAWANDA, NEW YORK.

CARD-INDEX DEVICE.

Application filed January 25, 1923. Serial No. 614,810.

To all whom it may concern:

Be it known that I, JAMES H. RAND, Jr., a citizen of the United States, residing at Tonawanda, in the county of Erie and State of New York, have invented a new and useful Improvement in Card-Index Devices, of which the following is a specification.

This invention relates to improvements in index or record devices, and more particularly to that type of index in which a plurality of cards or card holders are removably supported in a tray or other supporting device in overlapping series, the edges of successive cards projecting one beyond the other.

Heretofore indexes or record card holders of this type have been provided comprising two sections, one section being provided with tongues or other means for effecting its attachment to a support, the other section embodying a card or card-holder provided with tongues or other parts adapted to releasably engage parts of the first-mentioned section, whereby the two may be readily secured together on the support. In devices of this kind where the index comprises a plurality of card-holders having sheaths or other means for releasably holding cards on the holders, various types of signal devices have been provided for drawing attention to a particular card or cards. As the attaching sections must of necessity be relatively heavy and more nearly rigid than the card members, the attachment of each card to the support by means of a separate relatively heavy or thick attaching portion substantially limits the number of cards that may be placed in a tray or drawer of given size.

The objects of the present invention are to provide card-holders, a plurality of which are adapted to be supported in a tray or other support and which have attaching sections which occupy little space on the support, but each of which effectively supports a plurality of cards; also to provide card-holders which will effectively support a plurality of cards of different sizes or forms; also to provide card-holders having means for attachment to a support and which effectively hold a plurality of cards in different positions, thereby permitting any desired number of cards in the index to be retained in positions wherein the cards themselves serve as signals in directing the operator's attention to such card or cards

when handling the index; and also to provide improvements in record or index cards and card-holders in the other respects hereinafter set forth and claimed.

60

In the accompanying drawings:

Fig. 1 is a plan view of a card-holder and cards embodying the invention.

Fig. 2 is an edge view thereof.

Fig. 3 is a perspective view of a portion 65 of the holder.

Fig. 4 is a portion of a plan view of one of the cards.

Fig. 5 is a section on line 5—5, Fig. 1, but 70 with the cards removed.

Fig. 6 is a perspective view showing the cards in different positions with respect to their holders.

Fig. 7 is a section on line 7—7, Fig. 1.

Fig. 8 is a plan view of a holder with one 75 card thereon.

Fig. 9 is a plan view of a holder with cards of different sizes supported thereon.

Fig. 10 is a section on line 10—10, Fig. 9.

Fig. 11 is a section on line 11—11, Fig. 9. 80

Fig. 12 is a plan view of a holder of another modified form, one of the cards thereon being broken away.

Fig. 13 is a plan view of the opposite face of the holder and cards shown in Fig. 12.

85

Fig. 14 is a section on line 14—14, Fig. 12.

Fig. 15 is a portion of a perspective view of the holder of Figs. 12 and 13.

Fig. 16 is a section of a pair of nested 90 holders of the form shown in Figs. 12 and 13.

The invention, generally stated, includes a card-holder having a part for attachment to a support and parts preferably hinged to said attaching part for removably supporting a plurality of record or index cards or slips, whereby one attaching part serves to hold any desired number of the removable cards or slips in the index. It further preferably includes means for supporting a plurality of record cards or slips in different positions relatively to one another whereby one or more cards or slips may be offset relatively to the others to produce a signalling effect. Further, means are provided for supporting cards of different sizes on one holder.

95

Referring to Figs. 1 to 7 inclusive, A designates, generally, a holder adapted to be attached to a support. For this purpose the holder is provided with suitable support-engaging means, such, for example, as the

100

105

110

- end tongues B, which, as well known in the art, are adapted to engage beneath the side flanges or guide members of a tray or drawer (not necessary to be here shown).
- 5 The holder is preferably provided with an upper, relatively stiff attaching portion C of which the tongues B are preferably integral parts. In the form of the present invention illustrated, two or more hinged parts 10 or members 10 are connected to the upper portion C. Any suitable number of these hinged parts or members may be provided, as it has been found that one holding member may be successfully used to support a 15 relatively large number of cards in the index device.
- These hinged portions 10, which may be constructed of material of less thickness or lighter weight than the upper portion C, 20 are provided with means for holding or supporting a suitable number of cards or the like. Thus there are provided on each hinged portion 10 a plurality of sets of parts for engaging and releasably holding 25 cards thereon. In the embodiment illustrated, the members 10 are each provided with a plurality of apertures 11 adjacent each side edge thereof and adapted to receive tongues 12 of the index cards 13. As 30 illustrated in Fig. 1 of the drawings, this plurality of apertures or attaching parts for the cards at both sides of the hinge members permits of the insertion of the tongues of one card in one set of apertures of one of the hinged members and the insertion of the tongues of another card of the same size in another set of apertures of the other hinge member, resulting in one of the cards being offset laterally relatively to the other. 35
- 40 As shown in Fig. 1, an edge of the rear card projects to the right of the figure beyond the front card and it is, therefore, apparent that in using the index, the attention of the operator will be readily called to the cards so offset. These improved holders also permit of the ready support of different sized cards upon the attaching means, illustrated, for example, in Fig. 6, where the front card, 45 which is shown thrown back in said figure, is of larger size than the rear card. This renders possible the ready association, on a common holding member in an index of a plurality of associated or cooperating cards or index members, which while bearing some 50 relation to one another, may preferably be of different appearance or form. The broken lines in Fig. 1 indicate the positions of an adjacent holder and cards in an index set or series.
- 55 As illustrated in Figs. 8 to 11 inclusive, each of the hinged members of the holder may be readily adapted to support a plurality of cards of different sizes. Thus, for example, in these figures there is shown a hinged member 10 having apertures 11

which receive and support two cards designated respectively as 14 and 15. As illustrated, these cards may, if desired, be of different dimensions.

In the modified form shown in Figs. 12 to 16, the holder has an upper portion C' provided with tongues B' and a hinged body portion 10^b having parts for supporting a plurality of cards of different sizes or for supporting cards in different relative positions thereon. In the embodiment shown, the body member 10^b of the holder may be provided with a sheath or pocket-forming portion 16 which is adapted to receive an edge of the card or an index slip or the like. The body portion of the holder is provided with a plurality of parts for engaging separate cards or slips to be placed thereon. As illustrated, these may be in the form of slits or apertures arranged in sets. Thus, for example, Figs. 12 and 13 show two cards of different sizes, a card 14^b on the front of the holder and having its lower edge resting in sheath 16 and the corners of its upper edge in the upper slits 19 and a smaller card 15^b, the corner edges of which extend through the four slits 18, comprising a set. These figures also show slits 17 and 20 providing two other sets of holding parts for accommodating cards of still different dimensions.

As illustrated for example, in Figs. 1, 3 and 6, each of the several sets of apertures or slits which receive the tongues of the cards are offset relatively to the other set or sets whereby on any one of the holders a card may be offset relatively to another card held thereon to call such card or cards to the attention of the operator of the index.

The provision of a plurality of sets of card-holding parts on the member which is attached to the tray or support results in the insertion of a greater number of cards or index members in a tray or support of given length and also adapts the index without any change whatsoever, to handle cards of different dimensions, at the same time permitting the offsetting of cards relatively to one another, thereby doing away with the necessity for separate, detachable signal devices and the like.

I claim as my invention:

1. In index card holders, the combination of an attaching portion having parts for attachment to a support, and a plurality of card-supporting portions hinged to said attaching portion, each of said card-supporting portions having parts for engaging and supporting a plurality of separate cards.
2. In index card holders, the combination of an attaching portion having means for attachment to a support, and parts for holding a plurality of separate cards, certain of said card-holding parts being offset relatively to the others of said card holding parts, whereby one of said cards may be supported

on said card-holding parts in a position offset from the other of said cards.

3. In index card holders, the combination of an attaching portion having means for attachment to a support and parts for holding a plurality of separate cards, certain of said card-holding parts being offset laterally relatively to the others, whereby one of said cards may be held in a position offset laterally from the other of said cards.

4. In index card holders, the combination of an attaching portion having parts for engaging a support, and a hinged card-supporting portion, said card-supporting portion having parts for holding a plurality of separate cards of different sizes.

5. In index card holders, the combination of an attaching portion having parts for engaging a support, and a hinged card-supporting portion, said card-supporting portion having parts for holding a plurality of separate cards of different sizes, certain of said card-holding parts being offset relatively to the others, whereby one of said cards may be supported in a position offset laterally from the other of said cards.

6. In index card holders, the combination of an attaching portion having parts for engaging a support, and a card-supporting portion hinged to said attaching portion, said card-supporting portion having a plurality of sets of openings adapted to receive portions of a plurality of cards to be supported thereon.

7. In index card holders, the combination of an attaching portion having parts for engaging a support, and a card-supporting portion hinged to said attaching portion,

said card-supporting portion having a plurality of sets of openings arranged to receive portions of separate cards of different sizes, whereby a plurality of cards of different sizes may be supported thereon.

8. In an index card holder, a relatively stiff attaching portion having projecting parts adapted to engage a support, and a plurality of flexible flat card-supporting portions having parts secured in superimposed relation on said attaching portion, each of said flexible card supporting portions being provided with means for engaging and holding a card independently of said other card-supporting portions or the cards thereon.

9. In an index card holder, the combination of an attaching portion having parts for engaging a support, a plurality of separate card-receiving portions separately hinged to said attaching portion, and a plurality of sets of card-engaging parts on each of said card-receiving portions whereby each card-receiving portion is adapted to hold a plurality of cards.

10. In an index card holder, the combination of an attaching portion having parts for engaging a support, a plurality of separate card-receiving portions separately hinged to said attaching portion, and a plurality of sets of card-engaging parts on each of said card-receiving portions, said sets of card-engaging parts being offset relatively to each other, whereby each card-receiving portion is adapted to hold a plurality of cards each with at least one edge offset relatively to the edges of the other of said cards.

JAMES H. RAND, JR.
